UNITED STATES PATENT OFFICE.

ANDREW J. SANFORD, OF NEWARK, OHIO.

DESIGN FOR A DISH.

41,533.

Specification for Design.

Patented July 4, 1911.

Application filed February 11, 1911. Serial No. 608,136. Term of patent 14 years.

To all whom it may concern:

Be it known that I, ANDREW J. SANFORD, a citizen of the United States, residing at Newark, county of Licking, and State of Ohio, have invented a new, original, and ornamental Design for Dishes, of which the following is a specification, reference being had to the accompanying drawing, forming a part thereof.

The drawing is a perspective view of a dish showing my new design.

The leading features of my design comprise a dish of the sherbet glass character

having a foot portion with tapering facets and a bowl portion carried thereon, said facets continuing on said bowl portion, the said bowl portion having a horizontally arranged Grecian band or border above said facets as shown.

I claim:

The ornamental design for a dish, as shown and described.

ANDREW J. SANFORD.
